UNITED STATES PATENT OFFICE.

MARCUS LEONARD SNOW, OF WEST STERLING, MASSACHUSETTS.

DESIGN FOR A HANGING VASE.

Specification forming part of Design No. 5,120, dated July 11, 1871.

To all whom it may concern:

Be it known that I, MARCUS LEONARD SNOW, of West Sterling, in the county of Worcester and State of Massachusetts, have invented a new and original Design for Hanging Vases; and I do hereby declare that the following is a full, clear, and exact description thereof, which will enable others skilled in the art to make and use the same, reference being had to the accompanying drawing forming part of this specification, which drawing represents a side view, partly in section, of my new design.

This invention relates to a new ornamentation of a hanging vase or flower-pot, and to a new configuration of the lower part of the same.

It consists, first, in ornamenting the side or surface of the vase A with foliage *a* in imitation

of forest-leaves, and with one or more tinted borders, *b*. The invention also consists in forming a concave flange, *c*, on the bottom of the vase, so that an annular saucer is thereby formed around the lower part of the vase. An aperture, *d*, leads from the interior of the vase into this saucer, which thus receives the superfluous water.

I claim as my invention—

1. The design for a vase, ornamented as shown.
2. The design for a vase, ornamented and provided with a concave base-flange, as shown.

The above specification of my invention signed by me this 2d day of June, 1871.

MARCUS LEONARD SNOW.
